UNITED STATES PATENT OFFICE.

JOHN L. ARGENBRIGHT, OF CHICAGO, ILLINOIS, ASSIGNOR OF ONE-HALF TO JOHN W. JOHNSON, OF CHICAGO, ILLINOIS.

WOOD-FORMING MACHINE.

1,178,569.

Specification of Letters Patent. Patented Apr. 11, 1916.

Application filed October 22, 1914. Serial No. 867,934.

To all whom it may concern:

Be it known that I, JOHN L. ARGENBRIGHT, a citizen of the United States, residing at Chicago, in the county of Cook and State of Illinois, have invented new and useful Improvements in Wood-Forming Machines, of which the following is a specification.

This invention relates to a wood forming machine and more specifically to a machine for performing what is known as "inside cutting". In the specific modification of the invention herein disclosed, I have illustrated pattern forms and blanks for making toilet seats, but it is to be understood that the invention is by no means limited to practice in connection with this class of work, but may be carried out in connection with mirror frames, picture frames and in fact any kind of wood forming in which inside cutting or cutting involving similar problems is involved.

Machines for making toilet seats and analogous articles, as hitherto made, usually comprise a table, upwardly through which extends a rotary cutter shaft carrying a rotary cutter thereon which comprises wing cutter blades. The blank for the finished article is usually cut out at its center by a jig-saw to nearly the size required and then placed upon a pattern block. The pattern block with the cut-out blank upon it is then placed over the cutter shaft. Thereafter the blank is fed to the cutter until the edge of the pattern block impinges against the cutter shaft then the block with the blank upon it is moved around the cutter shaft in such a fashion as to rub the entire edge of the pattern form in the pattern block against the cutter shaft, which results in the knives cutting away the sawed edge on the blank and finishing it. The operation of such a machine as hitherto positioned is extremely dangerous for two reasons. In the first place, unless the knives are at rest when the pattern block and blank are placed over them, the lower edge of the block or the blank is apt to strike the rapidly rotating knives. A variety of injuries may result. The block may be knocked out of the workman's hands, split or otherwise injured, the knives may be broken, or, worst of all, one of the workman's hands may be jerked into the knives, etc. This danger, however, can be avoided and is avoided by all careful

workmen by never attempting to place a blank upon the knives without first stopping the machine. This practice necessitates stopping and restarting the machine for every blank to be cut. An even more serious danger, however, and one which it is impossible by any means or practice heretofore known to prevent, is that which is technically known as a "back cut". This occurs as the knives are being fed into the work. At such a time the knives have wood behind them as well as in front of them. If there is the slightest slip back in the manipulation of the blank, that is to say if the blank is not fed forward evenly, at every instant in its feed to the knives, and if the blank is allowed to draw back a very small degree, one or the other of the rapidly whirling knife blades will strike a solid blow upon the untouched wood behind them (usually upon the corner left behind the knives as they feed into the wood). It is impossible when this occurs, for the workman to resist the sudden violent blow upon the blank. The least serious and inevitable result is of course the spoiling of the blank because it is jerked from side to side by the rapidly whirling knives, as they hit it first in one place and then another, and split or mar it. Sometimes the pattern block is also ruined and often, when a back cut occurs, the knives are broken. These damages, however, are insignificant compared to the obvious danger to the workman. The sudden blow upon the work in his hands may of itself strain his wrist or break his fingers, etc., or if the work flies entirely off the machine, as it sometimes does, it may strike him or a flying part of a broken knife may strike him. The most frequent accident, however, is that the pattern block and blank, breaking out of control, suddenly jerks one of his hands into the knives.

It is an object of this invention to provide a wood forming machine wherein the work may be supplied to the machine without stopping the latter.

It is another object of this invention to provide a guide to guide the frame as it is lowered over the knives in such a fashion that it is impossible for the work to prematurely strike the knives.

It is another object of this invention to provide means whereby a back cut will be absolutely prevented and whereby the

knives must of necessity be fed regularly forward into the work at the beginning of the cut therein.

Other objects and advantages of the invention will appear as the description to follow proceeds.

In the drawings: Figure 1 is a plan view of a machine constructed in accordance with my invention. Fig. 2 is a sectional elevation thereof on the lines 2—2 of Fig. 1. Fig. 3 is an elevation showing the machine in a different position. Fig. 4 is a perspective view of a portion of the guide pin. Fig. 5 is a detail bottom plan view of the guide pin locking device. Fig. 6 is a rear end elevation of a portion of the machine.

In the drawings 1 represents the machine table through which projects upwardly the cutter shaft 2 having thereon the cutter knives 3 which are situated at some distance above the machine table 1. At its rear and opposite the cutter shaft 2, the table is provided with a boss 4 having therein a key-way 5 in which is mounted the slide 6 upon which is pivoted the plate 7 by means of the vertical bolt 8. To the plate 7 is hingedly connected the arm 9, for pivotal movement in a vertical plane. At its forward end the arm 9 is secured by screws 10 to a frame 11 having at its forward end the handle 12. In the frame 11 may be removably mounted the pattern block 13 having cut therein a pattern form 14. The frame 11 carries brackets 15, which by means of screws 16 and 17 secure the pattern block in place. The brackets 15 are turned over at their upper ends 18 as shown and are provided with screw threaded apertures to receive the bolts 19 by which the blanks 20 are firmly held upon the pattern blocks.

From the description so far, it will be apparent that the frame 11 controlled through handle 12 may be raised and lowered upon the hinge 9', may be swung laterally upon the bolt 8 or may be drawn backward and forward in the key-way 5 and that the inside edge of the pattern form 14 may be trailed around the shaft 2 to cut out the blank 20 to the form of the pattern form 14 by means of the knives 3 in a fashion analogous to the old manual operation.

I will now describe the guiding means forming an important part of my invention.

The table 1 is provided directly in front of the cutter shaft 2 with a small vertical opening into which may be introduced the turned down end 21 of a guide pin 22, the guide pin when thus introduced resting with its shoulder 23 against the top surface of the table 1. The lower turned down portion 21 of the guide pin is provided with an annular groove 22' and with a flattened face 24, as shown in Fig. 4. Upon the bottom of the table 1 is mounted a plate 25

which overlaps the vertical aperture in the table 1 to a small extent. The construction is such that the guide pin 22 may be inserted through its aperture in the table 1 when the flattened face 24 is opposite the edge of the plate 25. If the guide pin is then turned it will be locked into the table by the engagement of the plate 25 with the annular groove 22'. It can be removed by turning it again until the flattened face 24 comes opposite the plate 25.

The frame 11 is provided at the base of its handle 12 with an aperture 27 which is of peculiar formation. It comprises a substantially semi-circular recess 28 opening at right angles to the direction of the handle, which recess is in open communication with and is in fact a continuation of the pattern formed side 29 of the recess.

In operation and assuming that the frame 11 has been swung off to one side of the cutter shaft 2, a blank 20 is introduced into the frame 11. The frame 11 is then raised by means of a handle 12 and moved to a position such as that shown in Fig. 3, whereupon it is lowered until the notch 28 engages the upper end of the pin 22, the length of the pin being sufficient so that this engagement may take place before the pattern block is lowered sufficiently far to strike the knives. With the notch 28 and pin 22 in engagement, the frame is centered so that if lowered with the pin 22 and notch 28 continually in engagement, the pattern block and the cut out blank are centered so that neither can possibly strike the knives 3. It is obvious therefore that all the operator has to do is to swing the frame to such a position that the pin 22 engages the notch 28 and then drop the frame, meanwhile keeping a slight pressure to the right on the handle 12 to keep the pin and notch in engagement. By this means it is possible to put new work upon the knives without stopping the machine, a result which could hitherto only be obtained at considerable danger to the operator and only with the most careful manipulation. Having lowered the frame to the position illustrated in Fig. 2, the operator next begins to cut. With the work in the position illustrated in Fig. 2 it is obvious that it will be impossible for him to move the frame 11 in any direction except that which will bring the pin 22 out of notch 28. He thus simply pushes the handle 12 to the left, whereupon notch 28 is moved away from the pin 22 and the pattern formed edge 29 is trailed continuously across the pin. This operation results in moving the frame so that the knives will feed gradually and regularly forward into the wood. It is to be particularly noted that a back cut is rendered absolutely impossible because the knives can never get behind the position in which they started. If the operator does allow the

frame to swing back after once starting it, the pin 22 will simply go back along the path it has taken until it strikes the notch 28, and the frame can never get to a position such that the knives can strike untouched wood in the rear of their cut. As soon as the frame has been moved until a point at 30 (or thereabout) on the pattern formed edge 29 rests against the pin, the pattern form 14 has come up against the cutter shaft 2. At this point the pin 22 can be removed and the cut finished by trailing the pattern form 14 around the cutter shaft 2, the operator manipulating the frame by means of the handle 12. It is impossible to accidentally get a back cut from this time on. Back cuts only occur as the work is beginning. The center of the blank is all cut out before the forming operation is started. When the pin 22 has reached the point 30 or thereabout, the edge of the wood will be completely removed as far as the knives can reach for a long distance behind the knives and a slight slip back could not, by any possibility, result in a back cut.

I claim:—

1. In apparatus of the class described, a table, a rotary cutter having knives projecting vertically above the table, a frame movable toward and away from the knives for holding the work, a removable guide pin adjacent the cutter and projecting farther above the table than said knives, said pin being adapted to come into contact with the frame prior to the contact of the work with the knives.

2. The combination of a work engaging surface and a rotary cutter projecting axially therefrom, of a work support movable over said surface and also toward and from the same, a projection from said surface engaging the work support to control its movement parallel to said surface and extended to engage the work support in its movement toward said surface before the work comes into the range of the cutter, so that guiding contact between the work support and said projection may be established before the operation of cutting begins.

3. In apparatus of the class described, a table, a cutter mounted in the table, a frame for holding the work slidably and pivotally connected with said table and having a pattern form therein, means for guiding said frame independently of said pattern form at the beginning of the cut, a portion of said means being removable whereby the remainder of the cut may be made from said pattern form.

4. In apparatus of the class described, a table, a cutter mounted in said table, a frame pivotally and slidably mounted on said table and having a pattern form thereon, said frame being adapted to hold the work, and means to guide the frame at the beginning

of the cut, said means preventing a back cut, a portion of said means being removable whereby the remainder of the cut may be finished from the pattern form in the frame independently of said means.

5. In a wood forming machine, a table, a rotary cutter projecting above the table, a frame movably connected to the table and having an aperture therein having a pattern formed side and a recess in communication therewith, a guide pin mounted in the table and adapted to engage with the aperture and recess in the frame prior to the time the wood comes in contact with the knives, whereby the work may be placed in correct starting position in relation to the knives without striking the latter and must thereafter be correctly brought up thereto.

6. In a wood forming machine for inside cutting, a table, a rotary cutter, a frame slidably and pivotally connected to the table and provided with a handle having a pattern form therein and a guide block whereby the work may be seated upon the guide block in the frame while the latter is moved away from the cutter and the frame then raised swung back and lowered to bring the work to the knives, means coöperating with said pattern form to temporarily and positively maintain the work out of contact with the knives while the frame is being lowered to bring the work to the knives.

7. In a wood forming machine for inside cutting, a machine table, a rotary cutter projecting therethrough and having knives, a frame hinged to the table for vertical movement with respect thereto and also pivotally connected with the table to permit lateral movement with respect thereto and having a handle, a pattern block mounted in the frame and provided with a pattern form, means for removably securing a blank to the pattern block and a guide pin projecting upward from the table and adapted to enter an opening in the frame, whereby the frame may be raised away from the cutter, shifted to one side and a blank then introduced upon the pattern block, the frame thereafter raised and shifted back until the guide pin registers with the opening therein and thereupon lowered whereby the cutter cannot strike the work as the latter is lowered around it.

8. In a wood forming machine for inside cutting, a table, a cutter shaft projecting upwardly therethrough and having rotary cutting knives thereon above the table, a frame pivotally and slidably connected to the table, a pattern block mounted in the frame and having a pattern form therein to guide the blank as it is moved about the knives, means on the frame for removably securing a blank therein, a guide pin projecting upwardly from the table to a point above the top of the cutter shaft, said frame having a recess

therein to receive the guide pin whereby when said guide pin engages said recess while the frame is above the knives, the frame may be lowered without striking the knives against the pattern block or the blank.

9. In apparatus of the class described, a machine table, a cutter shaft having a rotary cutter thereon projecting through the table, 10 a frame mounted to swing horizontally with respect to the table to slide back and forth with respect to the cutter shaft and to be raised and lowered with respect to the table and adapted to carry an apertured blank, an 15 aperture in the frame having a notch therein, said notch being in direct communication with a side of the aperture which is cut in a predetermined curve, whereby said frame may be raised above the knives, swung off to 20 one side, the blank mounted thereon, then swung back until the notch registers with the guide pin, lowered to bring the cutter up within the apertured blank and thereafter moved so that the curved side of the aperture travels along the said guide pin whereby the knives will be fed gradually into the work and steadily forward.

10. In a wood forming machine for inside cutting, a machine table, a cutter shaft projecting therethrough and cutter knives thereon, a frame pivotally, slidably and hingedly connected to the table and adapted to removably hold a blank thereon, said frame having an aperture therein provided 35 with a notch, a guide pin projecting upwardly from the table and extending farther than the rotary cutting knives whereby when the notch in the aperture in the frame is in engagement with the guide pin and the 40 frame is lowered upon the table, said frame can be moved only in a direction to bring the guide pin out of the notch and the work can thus be fed in one direction only at the beginning of the cut.

11. In apparatus of the class described, a machine table, a cutter shaft projecting therethrough having cutting knives thereon, said knives being spaced from the table, a frame pivotally, slidably and hingedly con-

nected with the table, a pattern block 50 mounted in the frame, means on the frame for removably securing a blank upon the pattern block, an aperture through the frame having a curved side terminating with and in communication with a recess, a 55 guide pin projecting upwardly from the table above the cutting knives, said recess being so located when the frame is lowered with the recess in engagement with the guide pin, the blank will be lowered about 60 the knives without striking the latter and whereby the frame can thereafter be moved with respect to the knives only in a direction to bring the guide pin out of the recess and cause the curved side of the aperture to 65 slide past the guide pin whereby the knives can only be fed forwardly into the work and a back cut is prevented.

12. In apparatus of the class described, a table, a rotary cutter projecting therethrough, a frame hingedly connected with the table and having an aperture therein, a guide pin projecting above the table farther than the cutter, means for attaching an apertured blank to the frame, all so constructed and arranged that when the top of the guide pin is in engagement with the aperture in the frame the blank will be above the cutter.

13. In apparatus of the class described, a 80 table, a cutter shaft projecting upwardly therethrough, a frame movably connected with said table and adapted to hold the blank, and means whereby the frame is guided at the beginning of the cut so that 85 the knives must be fed regularly and steadily forward into the wood and contact of said knives with the wood behind them during the beginning of the cut is prevented and other means for guiding the work during the remainder of the cut.

In witness whereof, I hereunto subscribe my name to this specification in the presence of two witnesses.

JOHN L. ARGENBRIGHT.
